US00D799258S

(12) **United States Design Patent** (10) **Patent No.:** **US D799,258 S**
Bann et al. (45) **Date of Patent:** **** Oct. 10, 2017**

(54) **PITCHER**

- (71) Applicant: **Takeya USA Corporation**, Huntington Beach, CA (US)
- (72) Inventors: **Yukio Bann**, Osaka (JP); **Sumitra Israchanpanich**, Huntington Beach, CA (US)

- (73) Assignee: **Takeya USA Corporation**, Huntington Beach, CA (US)

(**) Term: **15 Years**

(21) Appl. No.: **29/551,316**

(22) Filed: **Jan. 12, 2016**

Related U.S. Application Data

- (62) Division of application No. 29/488,781, filed on Apr. 23, 2014, now Pat. No. Des. 750,426.

(57) **CLAIM**

The ornamental design for a pitcher, as shown and described.

DESCRIPTION

FIG. 1 is a top, front, and side perspective view of a pitcher showing our new design;

FIG. 2 is a side view thereof;

FIG. 3 is a side view thereof;

FIG. 4 is a rear view thereof;

FIG. 5 is a front view thereof;

FIG. 6 is a top view thereof; and,

FIG. 7 is a bottom view thereof.

The broken lines in the drawing depict portions of the pitcher that form no part of the claimed design.
